UNITED STATES PATENT OFFICE

WALTER M. WOLF, OF CHICAGO, ILLINOIS

DESIGN FOR A CIGAR LIGHTER

Application filed February 20, 1931. Serial No. 38,749. Term of patent 14 years.

To all whom it may concern:

Be it known that I, WALTER M. WOLF, a citizen of the United States, residing at Chicago, in the county of Cook and State of Illinois, have invented a new, original, and ornamental Design for Cigar Lighter, of which the following is a specification, reference being had to the accompanying drawings, forming a part thereof, and in which—

Figure 1 is a side elevation of a cigar lighter showing my new design.

Figure 2 is a front elevation.

I claim:

The ornamental design for cigar lighter, as shown.

WALTER M. WOLF.
